[57] **CLAIM**

The ornamental design for a golf bag cover, as shown and described.

DESCRIPTION

FIG. 1 is a front elevational view of a golf bag cover in the folded position, showing my new design;

FIG. 2 is a front elevational view in use;

FIG. 3 is a rear elevational view thereof;

FIG. 4 is a front elevational view with the hood raised;

FIG. 5 is a top plan view with the hood lowered; and,

FIG. 6 is a side elevational view, the opposite side being a mirror image thereof.
